Primary Examiner — Paula Greene(74) *Attorney, Agent, or Firm* — Additon, Higgins & Pendleton, P.A.(57) **CLAIM**

The ornamental design for a wireless audio headset, as shown and described.

DESCRIPTION

FIG. 1 is a front perspective view of a wireless audio headset in accordance with the present design;

FIG. 2 is a front elevation view thereof;

FIG. 3 is a back elevation view thereof;

FIG. 4 is a left elevation view thereof;

FIG. 5 is a right elevation view thereof;

FIG. 6 is a top elevation view thereof; and,

FIG. 7 is a bottom elevation view thereof.

Broken lines shown in the drawings of the wireless audio headset are for illustrative purposes only and form no part of the claimed design.

1 Claim, 7 Drawing Sheets(56)
